(57) **CLAIM**

The ornamental design for a trigger-point massaging device, as shown and described.

DESCRIPTION

FIG. 1 is a perspective top, front and side view of a trigger-point massaging device;

FIG. 2 is a top view thereof;

FIG. 3 is a bottom view thereof;

FIG. 4 is cross-section view thereof as taken along line 4-4 in FIG. 2;

FIG. 5 is a side view thereof; and,

FIG. 6 is an end view thereof.

The arrows, markings and labelling on both sides of the illustration in FIG. 2 depict cutline for the cross-section view of FIG. 4 and form no part of the claimed design.

1 Claim, 4 Drawing Sheets
